UNITED STATES PATENT OFFICE.

FREDERICK J. KRUEGER, OF DETROIT, MICHIGAN.

TRIPPLICATE MANIFOLDING BOOK OR PAD.

971,283.

Specification of Letters Patent. Patented Sept. 27, 1910.

Application filed October 1, 1909. Serial No. 520,479.

To all whom it may concern:

Be it known that I, FREDERICK J. KRUEGER, a citizen of the United States of America, residing at Detroit, in the county of Wayne 5 and State of Michigan, have invented certain new and useful Improvements in Tripli-
cate Manifolding Books or Pads, of which the following is a specification, reference be-
ing had therein to the accompanying draw-
ings.

The invention relates to manifolding books or pads particularly designed for use where two copies for each original are required.

It is the object of the invention to facilitate the insertion and holding of the carbon sheet, and also the advancement of the same to a new position in the pad, as more fully hereinafter set forth.

In the present state of the art, triplicate manifolding pads have been formed in which the rear face of each sheet except the bottom one is carbonized, thereby dispensing with the necessity of the insertion of a 20 separate carbon sheet therebeneath. This construction is, however, objectionable, as the carbonized sheet, when removed and in contact with other papers, will soil the same. Another method which has been employed is 25 the binding into the pads a carbon sheet in each group, but this increases the bulk of the pad, and adds to the cost of the same by the large number of carbon sheets required. Still another method is to employ a plu-
30 rality of carbon sheets that are separately inserted between the different leaves of the group. This requires a separate handling of each carbon sheet and furthermore it is difficult to prevent the dropping out of the 35 sheets when the book or pad is not in use.

With my invention the objections above set forth are all avoided by providing a folded carbon sheet embracing the intermediate copy with the fold in close contact 45 with the edge of the sheet and positioned and retained thereby. This folded carbon sheet is furthermore provided with carbonized surfaces, which face in the same direction—or, in other words, the sheet be-
40 fore folding has its two portions carbonized upon reverse sides. Thus, after fold-
ing, one of the carbonized faces lies adjacent to the leaf embraced by the folded sheet and the other surface is in contact with the 50 next lower leaf.

In the drawings—Figure 1 is a perspec-

tive view of a book or pad constructed in accordance with my invention; Fig. 2 is a perspective view of the carbon sheet detached; Fig. 3 is a cross section through the 60 pad; Fig. 4 is a plan of the carbon sheet before folding.

A is a book or pad having its leaves ar-
ranged in groups of three.

B is the carbon sheet, which is formed 65 from a blank slightly greater than twice the size of the leaves and having carbonized faces C and D upon opposite sides of the portions lying on either side of a central line E. The sheet thus formed is folded 70 along the line E, which will cause the sur-
faces C and D to face in the same direction. The folded sheet is then inserted in the book so as to embrace the intermediate leaf, with the fold adjacent to one edge thereof, and 75 the construction is such that the upper por-
tion of the carbon sheet has a marginal por-
tion F projecting beyond the opposite edge 80 of the leaf. Thus the user may readily dis-
engage the carbon sheet by grasping this marginal portion and without danger of 85 clamping the intermediate sheet in tearing the same.

In use, the carbon sheet is first engaged 85 with the intermediate leaf of the first group, in which position it will be retained by the engagement of the fold with the edge of the sheet, and by the clamping effect of the op-
posite portions upon said sheet. Thus there 90 is little danger of accidental disengagement and loss of the carbon sheet. After the 95 filling out of the original, the user throws out the carbon sheet and places it in engage-
ment with the intermediate leaf of the next group, after which the filled-out copy may be drawn from the pad.

What I claim as my invention is:

1. The combination with a book or pad, 100 of an unbound folded carbon sheet adapted to embrace a leaf with the fold adjacent to the edge thereof, and a marginal portion projecting beyond the opposite edge of the leaf, the two portions of said carbon sheet having their carbonized surfaces facing in the same direction.

2. A manifolding book or pad comprising 105 a plurality of leaves bound together at one edge and having their remaining edges free, and an unbound carbon sheet folded to embrace a leaf intermediate two other leaves, and having portions upon opposite sides of the embraced leaf provided with 110

carbonized surfaces facing downward whereby a copy is formed on the embraced leaf, and the leaf beneath the same, an edge of one portion of the carbon sheet projecting beyond the corresponding edge of the other portion and beyond the edge of the leaves of the pad.

3. The combination of a book or pad comprising a plurality of leaves bound together at one edge, the remaining edges being free, and an unbound carbon sheet folded to embrace a leaf intermediate two other leaves, and having portions upon opposite sides of the embraced leaf provided with carbonized surface facing downward, whereby a copy is formed upon the embraced leaf and the leaf beneath the same.

4. A manifolding book or pad, comprising a plurality of leaves arranged in series of three and bound together at one edge, the remaining edges of said leaves being free, and a removable carbon sheet folded to form parallel leaves adapted to be positioned upon opposite sides of the intermediate leaf of the series, said parallel leaves being carbonized on one side only and facing in the same direction, and one of said carbon leaves having a marginal portion projecting beyond the other, and beyond the corresponding marginal portion of the leaves of the book.

5. The combination with a book or pad, comprising a plurality of leaves of substan-

tially the same size bound together at one edge and having their remaining edges free, of a folded carbon sheet adapted to embrace one of the leaves of the pad and having portions upon opposite sides of said leaf with carbonized surfaces facing in the same direction whereby a copy is formed on the embraced leaf and also the leaf beneath the same, one of the portions of the carbon sheet being of substantially the same size as the leaves of the pad and the other portion of the carbon sheet being of slightly greater width than the leaves.

6. The combination with a book or pad, comprising a plurality of leaves bound together at one edge, of an unbound carbon sheet folded to embrace the leaf intermediate two other leaves, and having portions upon opposite sides of the embraced leaf provided with carbonized surfaces facing downward whereby a copy is formed on the embraced leaf and the leaf beneath the same, the portion of the carbon sheet above the embraced leaf having an edge projecting beyond the corresponding edge of the other portion of the carbon sheet and beyond the edge of the leaves of the pad.

In testimony whereof I affix my signature in presence of two witnesses.

FREDERICK J. KRUEGER.
